(57) **CLAIM**

The ornamental design for a cover for shopping carts, as shown and described.

DESCRIPTION

An visually appealing and discrete ornamental design for a shopping cart that features a discrete cover as an effective means of protecting purchases from inclement weather while walking to the automobile.

FIG. 1 is a top perspective view of a cover for shopping carts showing my new design;

FIG. 2 is a bottom perspective view;

FIG. 3 is a side perspective view;

FIG. 4 is the back perspective view;

FIG. 5 is the front perspective view; and,

FIG. 6 is the isometric perspective view of the design being used on a shopping cart.

The broken line showing of a cart in FIG. 6 is included for the purpose of illustrating environment and forms no part of the claimed design.
